J. H. RICHARDS

BOX OPENER

Filed June 29, 1926

Fig: 1.

10 Inventor
11 JOHN H. RICHARDS,
By Clarence A. O'Brien. Attorney

UNITED STATES PATENT OFFICE.

JOHN H. RICHARDS, OF YAKIMA, WASHINGTON.

BOX OPENER.

Application filed June 29, 1926. Serial No. 119,352.

This invention relates to box opening devices, and has more particular reference to a means for facilitating the removal of box lids wherein the lids are secured to the box 5 by transverse cleats or strips at the opposite ends thereof, this type of box being usually employed in the shipment of apples.

The primary object of the invention is to provide a box opener wherein the lid may 10 be quickly removed by two simple operations, and this without damaging the cleats or lids which is substantially impossible in the opening of this type of box with other tools.

15 The invention further aims to provide a device for facilitating the entire removal of a box lid attaching cleat or strip in one operation, and this without requiring any skill whatever upon the part of the person 20 employing the present opener.

Other objects will become apparent as the nature of the invention is better understood, the same comprising the novel form, combination and arrangement of parts hereinafter more fully described, shown in the 25 accompanying drawing and claimed.

In the drawing wherein like reference characters indicate corresponding parts throughout both of the views:

30 Figure 1 is a side elevation of a box opener constructed in accordance with the present invention, the same being shown as actually in use, and

Figure 2 is a view taken substantially upon 35 the line 2—2 of Figure 1 and looking downwardly in the direction of the arrows.

Now having particular reference to the drawing, my novel box opener constitutes the provision of a metallic plate 5 of suitable 40 width and of a length substantially equivalent to the width of a conventional apple box designated A in Figure 1. This plate is of concavo-convex formation in the direction of its width so as to permit the same to be 45 rocked upon the lid B of the box when in use, said plate being equipped with a suitable form of rocking handle 6 that is bolted or otherwise-suitably secured at one end to the inner face of the plate intermediate the 50 ends thereof, and extending substantially vertically therefrom as clearly disclosed in Figure 1.

The forward edge of the plate 5 is preferably sharpened and formed upon the inner 55 face of the plate in slight spaced relation with the sharpened edge, are spaced vertical

lugs 7 preferably four in number, and traversing those of which are at the opposite sides of the plate are rigid pivot pins 8—8.

The opener further constitutes the provision of a pivoted plate 9, the inner edge of which is formed with a pair of extensions 10—10 of a length slightly lesser than the space between the lugs at opposite sides of the center of the rocking plate 5, which extensions are formed at their longitudinal edges, with hinged knuckles 11—11, through which the previously mentioned pivot pins 8—8 extend.

The forward edge of the plate 9 is bent 70 downwardly a slight distance as at 12, and thence inwardly for providing a cleat biting lip 13, the edge of which is toothed as indicated at 14 in Figure 2 for facilitating a biting grip upon the box lid securing cleat 75 or strip C, at the forward edge thereof. When using the tool, the parts are arranged as shown in Figure 1 whereby the forward sharpened edge of the curved plate 5 is disposed adjacent the inner side of the cleat 80 or strip C and the teeth 14 of the lip 13 engage the outer side edge of the cleat or strip.

Obviously, when the tool is arranged with respect to the box as disclosed in Figure 1, a rearward pull upon the handle 6 will cause 85 the sharpened edge of the plate 5 to engage beneath the cleat or strip C and the box lid B, in order that as the plate is rocked upon the lid, said cleat or strip will be forced upwardly, this upward movement being further assisted by reason of the pivotal plate 9, the lip of which has firm engagement with the front side of said cleat or strip, resulting in the efficient and rapid removal of the cleat or strip from the box and this without great- 95 ly marring the cleat or strip and the box lid.

It will thus be seen that I have provided a highly novel, simple and efficient form of box opener that is well adapted for all of the purposes heretofore designed, and even 100 though I have herein shown and described the invention as consisting of certain detail structural elements, it is nevertheless to be understood that some changes may be made without affecting the spirit and scope of the 105 appended claims.

Having thus described the invention, what I claim as new, and desire to secure by Letters Patent is:

1. In an opener for cleated boxes, an elongated plate member of substantially the same width as the lid of the box to be removed,

said plate being curved transversely throughout its entire length, for facilitating the rocking of the same upon the box lid, a handle extending upwardly from the rear edge portion of said plate for rocking the same, the forward edge of said plate being sharpened and adapted to be disposed against the inner side edge of the cleat, ears extending upwardly from the concaved face of the rockable plate at spaced intervals and provided with registering openings, a flat plate, knuckles formed on the inner edge of said flat plate and adapted for disposition between the aforementioned lugs, a pivot pin extending through the lugs and the knuckles whereby the flat plate is pivotally secured to the rockable plate, the forward edge portion of said flat pivoted plate extending beyond the forward sharpened edge of the rockable plate, the outer edge portion of said pivoted plate being disposed downwardly and thence inwardly to provide a cleat engaging lip, the free edge of said lip being serrated and engaging the outer side edge of the cleat.

2. In an opener for cleated boxes, an elongated plate curved transversely throughout its entire length, the convex face thereof being adapted for rockable movement on the lid of the box, a handle extending upwardly

from the rear edge portion of said rockable plate for actuating the same, the forward edge of said plate being sharpened and adapted for engagement with the inner side edge of the cleat, ears extending upwardly from the concaved face of the rockable plate at spaced intervals and provided with registering openings, a flat plate, knuckles formed on the inner edge of said flat plate and adapted for disposition between the aforementioned lugs, a pivot pin extending through the lugs and the knuckles whereby the flat plate is pivotally secured to the rockable plate, the forward edge portion of said flat pivoted plate extending beyond the forward sharpened edge of the rockable plate, the outer edge portion of said pivoted plate being disposed downwardly and thence inwardly to provide a lip, and teeth formed in the free edge of said lip adapted to bite into the outer side edge of the cleat.

In testimony whereof I affix my signature.
JOHN H. RICHARDS.
